UNITED STATES PATENT OFFICE.

DAVID MAXWELL, OF PARIS, ONTARIO, CANADA.

HARVESTING-MACHINE.

SPECIFICATION forming part of Letters Patent No. 256,151, dated April 11, 1882.

Application filed August 29, 1881. (No model.)

To all whom it may concern:

Be it known that I, DAVID MAXWELL, of the town of Paris, in the county of Brant, in the Province of Ontario, Canada, have invented 5 new and useful Improvements in Harvesting-Machines, of which the following is a specification.

The object of the invention is to brace the finger-beam on its top side at the point where 10 the rake-standard is carried; and it consists essentially of a bar or rod attached at one end to the finger-beam, near the post or inner end of the beam, and at its other end to a bracket situated upon and attached to the finger-beam 15 at a point near the rake-standard, the said rod being provided with suitable adjusting mechanism arranged to exert through the rod a pushing strain upon the two points connecting it to the finger-beam, substantially as herein- 20 after explained.

The drawings represent a sectional elevation of a portion of the finger-beam, showing the rake-standard and the post for connecting the beam to the main frame of the machine.

25 Figure 1 shows the bracing-rod connected at one end to the finger-beam by a bolt passing therethrough, from whence the brace extends obliquely in an upward direction, through a passage-way made in the rake-standard, to a bracket bolted on the finger-beam outside of the rake-standard. Fig. 2 is a similar view, 30 showing the bracing-rod connected at one end on the bottom end of the post, below the finger-beam, and extending obliquely in an upward direction to a bracket situated on the outside of the rake-standard. Fig. 3 shows two rods, 35 one on each side of the rake-standard, running parallel with the finger-beam and connected at either end to brackets, one situated near the inner end of the finger-beam and the other outside of the rake-standard.

I have shown my brace applied in three different ways. There are, of course, other ways of attaching the brace for accomplishing the 45 same purpose; but the plans illustrated will be sufficient to explain the invention. The important point to be observed in arranging the brace is to see that the inner end of the rod is situated above the finger-beam.

50 Heretofore it has been customary to brace the finger-beam by a brace extending along its

bottom. This brace is not only constantly in the way, coming in contact with obstructions on the ground, but it does not effectually support the finger-beam at the point where it 55 usually sags—viz., at the point where the rake-standard is situated.

A is the finger-beam; B, the post for connecting the beam to the main frame of the machine. C is the brace for staying the post B. 60 D is the rake-standard. E is the bar or rod forming my brace. F is a bracket situated outside of the rake-standard and provided with a socket, a, into which the end of the brace fits. G is a bolt passing through the finger-beam 65 for securing the bracing-rod when arranged as shown in Fig. 1. H is a bracket situated on the inside of the finger-beam when the brace is to be arranged as shown in Fig. 3. I is a nut screwed upon the end of the brace E at the 70 point where it enters the bracket F.

When the bracing-rod E is placed in position the nut I is screwed against the bracket F, producing a pushing strain on the rod E, thereby causing the finger-beam to buckle upwardly 75 between the two points at which the bracing-rod E is connected to it. Instead of the nut, the same effect could be produced by a wedge-key, or other mechanical devices might be designed to effect the same purpose. I therefore do 80 not limit myself to any particular mechanical means for exerting the desired pushing strain against the points referred to; nor do I confine myself to any particular number of rods or their exact location, except that the end of 85 the bracing-rod near the rake-standard shall be above the finger-beam.

I may also state that while it will be necessary, in order to secure the full benefit of my invention, that the outer end of the rod E shall 90 be connected to the finger-beam at a point outside of the rake-standard, the same effect would, in a measure, be secured by connecting it close to the rake-standard, even if it did not extend beyond it.

95 In the foregoing description I have referred to the brace as designed to support the weight of the rake-standard. In addition to accomplishing this object, the same brace may be utilized to strengthen the finger-beam to resist an upward strain, which object may be 100 effected by extending the end of the rod E

through the bracket F and placing upon the rod, on the outside of the bracket, an additional nut, I', as shown in Fig. 2.

What I claim as my invention is—

- 5 1. In a harvesting-machine, the combination, with the finger-beam, of a bar or rod connected at one end to the finger-beam, near the post or inner end of the beam, and at its other end to a bracket situated upon and attached to the finger-beam at a point outside of the rake-standard, and provided with means, substantially as described, to exert a pushing strain on said bar, as and for the purpose specified.
- 10 2. In a harvesting-machine, a bar or rod connected at one end to the finger-beam, at or near the inner end thereof, and extending obliquely in an upward direction to a point above the finger-beam and near the rake-standard, at which point it is adjustably connected to the
- 15 3. finger-beam, in combination with means, substantially as described, by which a pushing strain can be exerted through the rod upon the

two points connecting it to the finger-beam for the purpose of bracing the latter at the point where the rake-standard is carried.

25

3. In a harvesting-machine, in combination with the finger-beam, a bar or rod secured above said finger-beam, and means, substantially as described, for exerting a pushing strain on said bar or rod for the purpose of bracing the finger-beam, substantially as specified.

4. In a harvesting-machine, a bar or rod rigidly attached to the inner end of the finger-beam, and extending therefrom to a bracket attached to the finger-beam outside of the rake-standard, in combination with nuts I and I', screwed upon the rod and arranged to jam against the bracket F, substantially as and for the purpose specified.

35

DAVID MAXWELL.
